PNEUMATICALLY OPERATED CIRCUIT
INTERRUPTERJohn B. MacNeill, Wilkinsburg, Pa., assignor to
Westinghouse Electric Corporation, East Pitts-
burgh, Pa., a corporation of Pennsylvania

Application February 23, 1951, Serial No. 212,373

12 Claims. (Cl. 200—82)

1

This invention relates to circuit interrupters and more particularly to compressed air operated circuit interrupters.

An object of the invention is to provide a pneumatically operated circuit interrupter which may be tripped open free of the operating means.

Another object of the invention is to provide a circuit interrupter of the compressed gas operated type that may readily be assembled for trip-free or non-trip-free operation.

Another object of the invention is to provide a circuit interrupter embodying a novel trip-free operating mechanism which can readily be changed to a non-trip-free mechanism or vice versa.

Another object of the invention is to provide a circuit interrupter embodying a novel operating mechanism which is capable of assembly as a trip-free or a non-trip-free mechanism by adding or omitting a minimum of parts.

Another object of the invention is to provide a circuit interrupter of the compressed gas operated type that is trip free of the operating mechanism which can be made non-trip-free of the operating mechanism by the elimination of one of the elements.

The novel features that are considered characteristic of the invention are set forth in the appended claims. The invention itself, however, both as to structure and operation, together with additional objects and advantages thereof will be best understood from the following detailed description thereof when read in connection with the accompanying drawings.

In said drawings:

Figure 1 is an elevational view partly in section of a circuit breaker operating mechanism embodying the principles of the invention.

Fig. 2 is a top plan view of the operating mechanism.

Fig. 3 is a detail plan view of a part of the latching mechanism.

Fig. 4 is a fragmentary elevational view partly in section showing the operating mechanism arranged for non-trip-free operation.

Referring to Fig. 1 of the drawings, the circuit interrupter, shown schematically at 1 may be of any conventional construction either of the oil break or air break type. The circuit breaker as schematically shown, comprises stationary contact means 9 and movable contact means 11. Although illustrated as a single pole circuit interrupter, it will be understood that the interrupter may have a set of contacts 9 and 11 for each pole thereof with the movable contacts 55

2

mechanically connected for simultaneous operation in the usual manner.

The circuit interrupter is biased to open circuit position by means of an accelerating spring 15, and the interrupter is mechanically connected to the operating mechanism indicated generally at 17 by a suitable connecting means comprising a lever 19 pivoted at 21 on a fixed support. One end of the lever 19 is pivotally connected to a breaker lift rod 23 and the other end is pivotally connected to an operating rod 25 which is, in turn, connected to the operating mechanism 17.

The operating mechanism comprises a main casting 27 which is formed to provide a cylinder 29 closed at the upper end by an integral part of the casting. A closure member 31 suitably secured to the lower end of the cylinder 29 is provided with a relatively large port 33 open to the atmosphere.

Disposed in the cylinder 29 is an operating piston 35 secured by means of a nut 37 to a piston rod 39. The piston rod 39 extends through a substantially air tight opening in the upper end of the casting 27 and is pivotally connected by means of a pin 41 to a pair of outer levers 43 (Figs. 1 and 2). At their left hand ends the levers 43 are pivotally supported on the upper end of links 45 by means of a pin 47, the lower end of the link 45 being pivotally supported by means of a pin 49 pivoted in a pair of spaced ears 51 (only one being shown) formed integral with the casting 27. Also pivotally supported on the pin 47 is a pair of inner levers 53 which are pivotally connected by means of a pin 55 to the lower end of the breaker pull rod 25.

The right hand ends of the outer levers 43 are rigidly connected by means of a cross bar 57 suitably secured thereto, for instance, by welding. The levers 43 between them carry a pin 59 upon

which is mounted a latch roller 61 normally engaged by a main latch 63 to maintain the outer levers 43 in the closed position. Also mounted on the pin 59 is a latch 65 which normally engages a latch roller 67 mounted on a pin 69 supported between the inner levers 53 to maintain the inner levers 53 and the interrupter in closed position. The latch 65 comprises a pair of spaced latch members disposed one on each side of the main latch 63 and rigidly connected by means of a pin 71. The latch 65 is biased to latching position by means of a compression spring 73.

The main latch 63 is pivotally mounted on the casting 27 by means of a pin 75 and is biased to latching position by a compression spring 77. The main latch 63 is of the slip-off type, that is, its

latching configuration is such that it will not, of itself, restrain the mechanism against the opening force of the accelerating spring 15. A secondary latch 79 is provided to hold the main latch in latching position. The secondary latch 79 is pivoted on the casting by means of a pivot pin 81 and is biased into latching engagement with the main latch 63 by a spring 83. The latch 79 has a tail piece 85, the free end of which is disposed above a trip rod 87 forming part of a tripping electromagnet indicated generally at 89. Also pivoted on the pin 81 is an arm 91 having its free end disposed above the trip rod to be engaged and actuated thereby. The arm 91 is provided with a projection 93 disposed beneath the tail 85 on the latch member 65 so that when the arm 91 is actuated the projection 93 engages the tail 85 and actuates the latch 65 to unlatching position.

The trip magnet 89 comprises a magnet yoke 97, an energizing coil 99 and a movable armature 101 attached to the lower end of the trip rod 87. The interrupter is tripped open by energization of the coil 99 which may be effected in any suitable manner, for instance, by the well known fault relay. Energization of the trip magnet 89 causes the armature 101 to move the trip rod 87 upwardly to actuate the arm 91 and the auxiliary latch 79. Actuation of the arm 91 causes the projection 93 to engage the tail 85 and actuate the latch 65 to unlatching position. This disconnects the inner levers 53 (Figs. 1 and 2) from the outer levers 43 and permits the accelerating spring 15 to move the movable contact means 11 and the breaker mechanism including the inner levers 53 toward the open position free of the outer levers 43 and the operating piston 35. At approximately the same time the auxiliary latch 79 is actuated to unlatching position by the trip rod 87 engaging the tail 85 thereof whereupon the force of a strong spring 103 (Fig. 1) compressed between the cylinder closure 31 and the piston 35 moves the piston and the piston rod 39 upwardly rotating the outer levers 43 counterclockwise. This action forces the main latch 63 to unlatching position permitting continued counterclockwise or retrieving movement of the outer levers 43. Since the latch 65 is pivoted on the pin 59 which is carried by the outer levers 43 the latch 65 moves therewith and during the opening movement of the breaker overtakes the inner levers and is reengaged with the latch roller 67 thereon to reconnect the inner and outer levers to thereby reconnect the breaker mechanism to the operating piston 35 at least by the time the breaker reaches full open position.

After the latch roller 61 (Fig. 1) is free of the latch 63, the spring 77 restores the latch to latching position. In order to prevent breakage of the parts when the breaker is operated to the closed position, it is necessary to prevent the auxiliary latch 79 from reengaging the latch 63 until the breaker is fully closed. This is accomplished by means of a holding lever 105 pivotally mounted on the pin 81. The holding lever 105 is provided with a projection 107 extending laterally beneath the tail 85 of the auxiliary latch 79 and also has a projection 109 adapted to be engaged by the lever 43 in the closed position of the breaker to hold the holding lever in the position shown. The holding lever 105 is biased to holding position by means of a spring 111 that is somewhat stronger than the spring 83 which biases the auxiliary latch 79 to latching position

so that when the lever 43 moves counterclockwise the spring 111 moves the holding lever 105 to engage the projection 107 thereon with the tail 85 of the auxiliary latch 79 and hold the latch in unlatching position.

The circuit interrupter is adapted to be closed by compressed gas admitted to the cylinder 29 above the piston 35. Compressed gas is admitted to the cylinder 29 from an auxiliary tank 113 (Fig. 1) through an inlet passage 115 controlled by a main inlet valve indicated generally at 117 secured to the side of the casting 27. Operation of the inlet valve 117 is controlled by an electromagnetically operated pilot valve 119.

The main inlet valve 117 and the pilot valve 119 are fully disclosed in Patent 2,408,199, issued September 24, 1946 to J. M. Cumming and R. C. Cunningham and assigned to the assignee of the present invention. For this reason, a detailed disclosure of these elements is not included herein, since, for a complete understanding thereof, reference may be had to the above noted patent.

The pilot valve 119 is operated by an electromagnet 121 which, when energized, causes opening of the pilot valve 119 to admit compressed gas from the tank 113 to operate the main inlet valve 117. Operation of the inlet valve 117 admits compressed gas to the upper end of the cylinder 29 which drives the piston 35 quickly downward to close to the interrupter.

When the mechanism is operated to the closed position, the operating lever 43 moves in a clockwise direction, and near the end of its closing movement, the latch roller 61 engages the inclined surface of the main latch 63. As the latch roller 61 passes along the inclined surface, the latch 63 is rotated counterclockwise until the roller passes the nose of the latch whereupon the spring 77 restores the main latch 63 to latching position. As the roller 61 passes the nose of the latch 63, the lever 43 engages the projection 109 on the holding lever 105 and rotates the holding lever to its normal position permitting the spring 83 to restore the auxiliary latch 79 to latching position.

The arm 91 is biased to normal position by gravity or by spring means (not shown) and returns to normal position as soon as the tripping magnet is deenergized. A cut-away portion is provided on the under side of the arm 91 to prevent interference of the projection 107 of the holding lever 105 therewith.

Should the breaker be closed against a fault on the line the tripping magnet 89 would be immediately energized to trip the breaker free of the closing means. The breaker would go immediately to the open position but the high-pressure air in the cylinder 29 would prevent quick recoupling of the closing mechanism to the breaker. In order to facilitate high-speed recoupling of the closing mechanism to the breaker and reclosing of the breaker there is provided an exhaust valve mechanism 123 (Fig. 2) which controls a relatively large exhaust port 125 (Fig. 1). The exhaust valve mechanism is fully disclosed in Patent No. 2,403,082, issued July 2, 1946 to A. W. Hill and J. M. Cumming, and assigned to the assignee of the present invention. A detailed disclosure of the exhaust valve mechanism is not included herein since reference may be had to the above noted Patent 2,403,082 for a complete understanding thereof.

The exhaust valve device 123 (Fig. 2) is operated to open the exhaust ports 125 (Fig. 1) by the high-pressure air in the cylinder 29 under

the control of a valve indicated at 127. The valve 127 controls a passage 129 communicating the cylinder 29 with a tube 131 (Fig. 2) which, in turn, communicates with the exhaust valve device 123. When the breaker closes in against a fault the tripping magnet 89 is energized and trips the breaker free of the closing mechanism in the previously described manner, and, at the same time, opens the valve 127 admitting high-pressure closing air from the cylinder through the passage 129 and tube 131 to effect opening of the exhaust valve device 123 which quickly dumps the high-pressure air from the cylinder. This permits the spring 103 (Fig. 1) to effect high-speed recoupling of the piston 35 to the breaker mechanism at least by the time the breaker reaches full open position. The circuit breaker is then closed in the previously described manner.

An important feature of the invention is that the interrupter may be assembled as a trip-free or non-trip-free interrupter by the inclusion or omission of one of the elements. Also the interrupter may readily be altered in the field from a trip-free to a non-trip-free mechanism or vice versa in the same manner.

All that is necessary to change the interrupter mechanism from trip-free to non-trip-free operation is to remove the latch 65 (Fig. 1) which releasably restrains the inner levers 53 in the closed position, and to replace the pin 69 upon which the latch roller 67 is mounted with a longer pin 133 (Fig. 4) which extends through both the inner levers 53 and the outer levers 43 thus coupling the breaker operating rod 25 directly to the piston rod 39. The mechanism is shown in Fig. 4 in this condition, that is, arranged for non-trip-free operation. It will be noted that the member 91 (Fig. 1) has also been eliminated from the Fig. 4 arrangement, however, this is merely a matter of convenience of assembly and, should the change from trip-free to non-trip-free operation be made in the field the element 91 may be left in place since, with the removal of the latch 65, the element 91 is without effect.

Having described the invention in accordance with the patent statutes, it is to be understood that various changes and modifications may be made in the structural details and combinations of elements disclosed without departing from some of the essential features of the invention.

I claim as my invention:

1. A circuit interrupter having a power operated closing means, a first lever connected to said interrupter, a second lever connected to said closing means, a common pivot for said levers, a first latch mounted on a fixed pivot for releasably restraining said first lever, a holding latch normally holding said first latch in latching position, a second latch mounted on said first lever for releasably restraining said second lever, and a single trip device operable to simultaneously engage and positively actuate said holding latch and said second latch to permit high-speed opening movement of said interrupter free of said closing means and to permit high-speed movement of said closing means to recouple said closing means to said interrupter.

2. A circuit interrupter comprising stationary and movable contact means, spring means biasing said movable contact means in opening direction, compressed gas operated means comprising a cylinder and a piston movable therein for actuating said movable contact means to closed position, a first lever connected to said

piston, a second lever connected to said movable contact means, a first main latch mounted on a fixed pivot for releasably restraining said first lever in closed position, an auxiliary latch releasably restraining said first main latch in latching position, a second main latch carried by said first lever releasably restraining said second lever and said movable contact means in closed position, and electromagnetic trip means operable to simultaneously actuate said auxiliary latch and said second main latch to effect opening movement of said movable contact means free of said piston.

3. A circuit interrupter comprising stationary and movable contact means, spring means biasing said movable contact means to open position, power means for actuating said movable contact means to closed position, a first lever connected to said power means, a second lever connected to said movable contact means, a common pivot for said levers, a first main latch mounted on a fixed pivot normally releasably restraining said first lever in closed position, an auxiliary latch mounted on a fixed pivot normally restraining said first latch in latching position, a second main latch pivotally mounted on said first lever normally releasably restraining said second lever and said movable contact means in closed position, and a trip device operable to simultaneously engage and positively actuate said auxiliary latch and said second main latch to effect opening movement of said movable contact means.

4. A circuit interrupter having power operated closing means, spring means for opening said interrupter, a pair of levers, one of said levers being connected to said interrupter and the other of said levers being connected to said closing means, latch means releasably restraining said other lever in operative position, said latch means being operable to permit opening movement of said one lever and said interrupter by said spring with associated movement of said other lever and said closing means, selectively insertable latch means operable to permit opening movement of said one lever and said interrupter by said spring without associated movement of said other lever and said closing means, and a trip device operable to effect unlatching operation of said latch means.

5. A circuit interrupter having power operated closing means, spring means for opening said interrupter, a pair of levers, one of said levers being connected to said interrupter and the other of said levers being connected to said closing means, pivot means pivotally supporting said levers at one end thereof, said levers having aligned openings therein adjacent the other end thereof for receiving a pin whereby said levers may be held in fixed relation to each other, latch means releasably restraining said levers in operative position, and a trip device for actuating said latch means to effect opening of said interrupter.

6. A circuit interrupter having stationary and movable contacts, spring means biasing said interrupter to open position, power operated means for closing said interrupter, a pair of levers, one of said levers being connected to said interrupter and the other lever being connected to said power operated means, pivot means pivotally supporting said levers at one end thereof, means including a pin and a latch for selectively connecting the other end of one lever for unitary movement with the other lever and to provide a releasable connection between said levers, and a trip device op-

erable to release said levers and effect opening of said interrupter.

7. A circuit interrupter having stationary and movable contacts, spring means biasing said interrupter to open position, power operated means for closing said interrupter, a pair of levers, one of said levers being connected to said interrupter and the other lever being connected to said power operated means, pivot means pivotally supporting said levers at one end thereof, a releasable restraining device for holding said lever connected to said power operated means, a removable element connecting said two levers at least when said lever connected to said power operated means is restrained by said releasable device, and a trip device operable to release said restraining device and effect opening of said interrupter.

8. A circuit interrupter having stationary and movable contacts, spring means biasing said interrupter to open position, power operated means for closing said interrupter, a pair of levers, one of said levers being connected to said interrupter and the other lever being connected to said power operated means, pivot means pivotally supporting said levers at one end thereof, a releasable restraining device for holding said lever connected to said power operated means, a latch removably mounted on one of said levers and releasably engaging a part on the other of said levers, a portion on each of said levers through which said two levers may be held in fixed relation to each other, and a trip device operable to release both said restraining device and said latch and effect opening of said interrupter.

9. A circuit interrupter having stationary and movable contacts, spring means biasing said interrupter to open position, power operated means for closing said interrupter, a pair of levers, one of said levers being connected to said interrupter and the other lever being connected to said power operated means, pivot means pivotally supporting said levers at one end thereof, a releasable restraining device for holding said lever connected to said power operated means, a latch mounted on one of said levers and releasably engaging a part on the other of said levers, aligned openings in each of said levers through which said two levers may be held in fixed relation to each other, and a trip device operable to release both said restraining device and said latch and effect opening of said interrupter.

10. A circuit interrupter having stationary and movable contacts, spring means biasing said interrupter to open position, power operated means for closing said interrupter, a pair of levers, one of said levers being connected to said interrupter and the other lever being connected to said power

5 operated means, pivot means pivotally supporting said levers at one end thereof, a releasable restraining device for holding said lever connected to said power operated means, a removable element connecting said two levers for movement in unison both when said restraining device is released and when said power operated means is operated, and a trip device operable to release said restraining device and effect opening of said interrupter by movement of both of said levers in unison.

10 11. In a circuit interrupter having power operated closing means, spring means biasing said interrupter to open position, a pair of pivoted levers, one of said levers being connected to said interrupter and the other lever being connected to said power operated closing means, restraining means releasably restraining said other lever in operative position, a latch removably mounted on said other lever and releasably engaging said one lever, said latch being operable to permit opening movement of said one lever free of said other lever and said power operated closing means, a pin removably mounted in said levers for connecting said levers for unitary movement, said latch and said pin being selectively mounted on said levers, and a trip device operable to release said levers and effect opening of said interrupter.

15 12. A circuit interrupter having spring means 20 for opening said interrupter to open position, closing means for closing said interrupter, a first pivoted element connected to said interrupter, a second pivoted element connected to said closing means, restraining means releasably restraining said second element in operative position, a latch removably mounted on one of said elements and releasably engaging a part of the other of said elements, said latch being operable to release said first element and effect opening movement of said first element free of said second element and said closing means, a member removably mounted on said elements for connecting said elements for movement of both of said elements, said interrupter and said closing means in unison, said latch and said member being selectively mounted on said elements, and a trip device operable to release said restraining means and effect opening of said interrupter.
